UNITED STATES PATENT OFFICE.

BOSE B. BOWERS, OF MACON, GEORGIA.

COMBINATION GRATE AND STOVE.

1,032,270.

Specification of Letters Patent.

Patented July 9, 1912.

Application filed September 25, 1911. Serial No. 651,179.

To all whom it may concern:

Be it known that I, BOSE B. BOWERS, a citizen of the United States, residing at Ma-
5 con, in the county of Bibb and State of Georgia, have invented new and useful Im-
provements in Combination Grates and Stoves, of which the following is a specifica-
tion.

This invention has reference to combina-
10 tion grates and stoves, and it resides, prima-
rily, in certain improvements, hereinafter de-
scribed at length, which relate to the con-
struction of the mantel that surrounds the
15 fire place, the casing connected to the man-
tel and containing the grate and its main
accessories, and the fire back also attached to
the aforesaid mantel.

A structural embodiment of the invention
20 is illustrated in the accompanying drawings,
whereof:—

Figure 1 is a front elevation of the im-
proved structure complete; Fig. 2 is a verti-
cal section taken on the line 2—2 of Fig. 1;
Fig. 3 is a sectional perspective view of the
25 mantel; Fig. 4 is a perspective view of a
modification of the invention; Fig. 5 is a front elevation showing the front piece
which may be substituted, under certain con-
ditions, for the casing; and Fig. 6 is a verti-
30 cal section taken on the line 6—6 of Fig. 5.

The improved device consists, as shown in
said drawings, of two main parts, the man-
tel, 5, which is disposed in front of the fire
place 6, and the casing 7. These parts may
35 constitute a single integral structure, as de-
picted in Fig. 4, or they may be formed sep-
arately and connected together in such a
manner as to admit of their ready detach-
ment from each other, for cleaning or other
40 purposes, as illustrated in Figs. 1, 2, and 3,
the latter construction being preferred.

The mantel is here shown as in the form
of a vertically disposed wall or plate having
formed therein, one above another, a series
45 of three openings 8, 9, and 10; the lower-
most opening 8 serves to permit the ash pan
11 to be inserted into and withdrawn from
its proper position relative to the parts here-
inafter described, while the next higher
50 opening 9 constitutes the discharge outlet
for the ashes into said pan, the top opening
10 being provided for the exit of the heated
air and products of combustion, and regis-
tering with the mouth of a flue 12 that con-
55 tains a pivotally-mounted damper 13 oper-
atively connected in any suitable manner

with a rod 14 whose front end projects
through an opening in the mantel. The
aforesaid flue is rigidly connected to said
mantel and may be an integral part thereof. 60

The casing is offset bodily, in a forward
direction from the plane of the mantel, as
shown in Figs. 2 and 4, and its top and bot-
tom walls 15 and 16 are inclined forwardly
and downwardly, and rearwardly and down-
wardly, respectively, the mutually-adjacent
65 forward edges of these walls being con-
nected by a central vertical wall 17. The
grate 18 is disposed within the casing and
may be supported by cleats 19, or the like, 70
in any way desired. In the construction
shown in Fig. 2, this element consists of a
rectangular frame 20 which rests on said
cleats and has pivotally mounted within it
the grate proper 21, one of the trunnions of 75
the grate projecting through openings on
the adjacent frame and casing sides and
having a handle 22 connected to it. The
front member of frame 20 is preferably pro-
vided with depending curved feet 23, which 80
rest upon the upper portion of wall 16, so
as to assist in supporting said frame and,
also, to support the grate proper in oper-
ative position. From the afore-mentioned
front frame member extend upwardly the 85
fire bars 24 which may be of the usual type
and are preferably integral with the frame.
These bars are disposed directly behind an
opening 25 formed in wall 17 and, therefore,
constitute the front of the open grate struc- 90

ture which is produced, in effect, when the
door 26 that closes said opening is lowered.
The fuel opening 27 is formed in the top
wall 15, in both forms of the invention,
and is normally closed by a hinged door 28. 95
In Fig. 2 there is also depicted a fire back 29
that is provided at its upper edge with a
rearwardly projecting supporting flange 30
that extends through opening 10 and rests
upon the bottom wall of flue 12, said flange 100
being formed adjacent its rear edge with a
lug 31, or other suitable device, adapted for
introduction through an opening 32, in said
flue wall. This back may also be used in
connection with the unitary structure shown 105
in Fig. 4, as will be understood, illustra-
tion thereof being considered unnecessary.

The above-described arrangement of
parts results in the entire casing being dis-
posed forwardly of the mantel, and, hence, 110
projecting into the interior of the room to be
heated, so that practically all of the heat

given off from the fuel will be thrown directly into the room. In consequence, much less fuel is necessary to heat the room than is required where the casing, or, at least, the greater portion thereof, lies within the fire place. Also, it is to be noted that all dust, ashes, and fine coal passing through the spaces between the grate bars will fall upon the rearwardly inclined lower wall of the casing and will slide down said wall through opening 9 directly into the ash pan, being thus conveyed completely out of the casing and prevented from escaping from the latter into the room. Finally, the full effect of an open grate may be readily produced, where the form depicted in Fig. 2 is employed, by merely opening the door 26, and, if desired, the door 28 as well, or the ordinary closed stove effect may be obtained when these doors are shut, the latter effect being presented at all times by the unitary structure shown in Fig. 4.

Where the detachable two-part construction is employed, the casing is preferably supported by means of a pair of hooks 33 that project laterally from the rear faces of the side extensions 34 with which the casing is provided. These hooks may be of any desired type, and they are designed to project through openings 35 formed in the mantel, their bills engaging the beveled lower walls of said openings. The rear face of the casing is also formed with a rectangular laterally projecting flange 36 that fits flush against the adjacent walls of the openings 9 and 10, and those of the depressed or rearwardly-offset central portion 37 of the mantel between those openings.

In connection with the construction just described, there is finally provided a supplemental front piece 38, depicted in Figs. 5 and 6, which is designed to be substituted for the casing, during warm weather, when no fire is necessary. This element consists merely of a flat plate adapted for detachable connection to the mantel in the same manner as the casing, (*i. e.*, by means of hooks and sockets).

The invention, its uses and advantages, are believed to be apparent from the foregoing, and further description is, accordingly, omitted.

Having fully described my invention, I claim:

1. A stove comprising, in combination, a vertically disposed mantel adapted to cover the opening in a fire place and provided adjacent its upper end with a rearwardly extending flue, and adjacent its lower end with a discharge opening for ashes; a casing connected to said mantel and offset as an entirety forwardly from the same, said casing being provided with an inclined upper wall extending downwardly and forwardly from a point adjacent the upper wall of said

flue, with an inclined lower wall extending downwardly and rearwardly to a point adjacent the lower wall of said discharge opening for conducting the ashes directly through the latter, and with a central wall connecting the mutually adjacent ends of said inclined walls; and a grate supported within said casing above the lower inclined wall. 70

2. A stove comprising, in combination, a vertically disposed mantel adapted to cover the opening in a fire place and provided adjacent its opposite vertical edges with a pair of openings; and an element provided upon its rear face with a pair of laterally-projecting hooks adapted to extend through the openings in said mantel and to engage the rear face of the latter for supporting said element in place on said mantel. 75

3. A stove comprising, in combination, a vertically disposed mantel adapted to cover the opening in a fire place and provided adjacent its opposite vertical edges with a pair of openings; a casing provided upon its rear face with a pair of laterally-projecting hooks adapted to extend through the openings in said mantel and to engage the rear face of the latter for supporting said casing in place on said mantel; and a grate disposed within said casing. 85

4. A stove comprising, in combination, a vertically disposed mantel adapted to cover the opening in a fire place and provided adjacent its opposite vertical edges with a pair of openings, and adjacent its lower end with a discharge opening for ashes; a casing provided upon its rear face with a pair of laterally-projecting hooks adapted to extend through the first-named openings in said mantel and to engage the rear face of the latter for supporting said casing in place on said mantel, said casing being offset as an entirety forwardly from said mantel and being formed with a downwardly and rearwardly inclined lower wall terminating adjacent the bottom wall of the second-named opening for conducting the ashes directly therethrough; and a grate supported within said casing above said inclined wall. 95 100 110

5. A stove comprising, in combination, a vertically disposed mantel adapted to cover the opening in a fire place and provided with a rearwardly extending flue having an opening therein; an element provided upon its rear face with a pair of laterally-projecting hooks adapted to extend through the first-named openings in said mantel and to engage the rear face of the latter for supporting said element in place on said mantel; and a fire back disposed against said mantel and covered by said element, said fire back being provided at its upper end with a rearwardly projecting supporting flange extending into said flue and formed with a depending lug engaged in the flue opening. 115 120 125 130

6. A stove comprising, in combination, a vertically disposed mantel adapted to cover the opening in a fire place and provided adjacent its lower end with a discharge opening for ashes; a casing connected to said mantel and offset as an entirety forwardly from the same, said casing being provided with a forwardly and downwardly inclined upper wall, with a rearwardly and downwardly inclined lower wall terminating at a point adjacent the lower wall of said discharge opening, and with a central wall connecting the mutually adjacent ends of said inclined walls and formed with an opening; 10 15 a grate disposed within said casing above

the lower inclined wall including a rotatably mounted series of grate bars and a frame wherein said bars are mounted, said frame being formed at its front end with a series of vertical fire bars extending directly 20 back of the opening in said central wall; and a door hinged to said central wall to cover and uncover the opening therein.

In testimony whereof I have hereunto set my hand in presence of two subscribing witnesses.

BOSE B. BOWERS.
